GRINDING WHEEL DRESSER

Henry W. Kropf and Arthur J. Brickner,
Muskegon Heights, Mich., assignors to Brick-
ner-Kropf Machine Company, Muskegon
Heights, Mich., a corporation of Michigan

Application September 28, 1942, Serial No. 459,930

1 Claim. (Cl. 125—11)

This invention relates to a grinding wheel dresser and it is particularly an improvement upon the device shown in the patent to Henry W. Kropf, No. 2,137,690, issued November 22, 1938.

The object of the present invention is to provide a mechanism adapted to facilitate the use of a grinding wheel dresser on a grinding machine, particularly for production work in which many articles of the same shape and size are located successively in the same position on the table of a grinding machine and requiring intermittent dressing of the grinding wheel, the periphery of which must be always maintained in conformity both to the desired shape of the article operated upon and in the correct position laterally of the movement of the table of the grinding machine.

The device embodies various novel features of construction and arrangement as hereinafter more fully described and particularly pointed out in the claims, reference being had to the accompanying drawings, in which,

Fig. 1 is an elevation of a portion of a grinding machine illustrating the grinding wheel, the work table and the grinding wheel dresser applied thereto.

Fig. 2 is a plan view of parts shown in Fig. 1.

Fig. 3 is a cross section on the line 3—3 of Fig. 1.

Fig. 4 is a cross section on the line 4—4 of Fig. 1.

Fig. 5 is an enlarged front view of the templet clamping and adjusting mechanism of the grinding wheel dresser.

Fig. 6 is a sectional elevation on the line 6—6 of Fig. 5.

Fig. 7 is a sectional elevation on the line 7—7 of Fig. 5, and

Fig. 8 is a plan view of the parts shown in Fig. 5.

Like numbers refer to like figures in the drawings.

1 represents the frame of the grinding machine having horizontal tracks 2 on which the work table 3 is mounted for horizontal reciprocation. Suitable and conventional means are provided for reciprocating the work table 3 but such operating means form no part of the present invention and are not shown.

A vertical head 4 extends upwardly from the rear part of the frame 1 and is provided with a conventional spindle supporting member 5 mounted for vertical adjustment on the front side of the head 4. The grinding wheel 6 is mounted on the spindle 7 and is rotated by con-

ventional means not shown and forming no part of the present invention.

For production work in which many articles of the same shape and size are to be successively operated upon, a jig 8 is rigidly attached to the reciprocating table 3 as by a bolt 9 having its head in a T-slot 10 in said table. Stops 11 are provided on the jig 8 against which the work 12 is located to insure proper lateral positioning and clamps 13 hold the work rigidly in place on the jig during the grinding operation.

The bed 15 of the grinding wheel dresser is rigidly attached to the reciprocating table 3 as by bolts 16 having their heads in the T-slot 10 in the table 3. When the bed 15 is attached to the table 3 it is immovable laterally and cannot be adjusted relative to the position of the work holding jig 8 and the work 12 thereon. The base 18, of the grinding wheel dresser rests upon the bed 15 and is freely movable in all horizontal directions. The dressing tool 19, which preferably is a diamond, is mounted on an arm 20 extending upwardly from the base 18 and is positioned in the same horizontal plane as the axis of the grinding wheel 6. A feeler 21 projects from the base 18 and has its point shaped the same as the point of the dressing tool 19 and located directly under it in a vertical plane. The feeler 21 is caused to traverse the face of the templet 22 during the dressing operation during which movement the base 18 is slid manually on the face of the bed 15.

The templet 22 has a shank 23 which is gripped in a clamp comprising a base 24 and a clamping bar 25 provided with screws 26. This clamp permits adjustment of the templet longitudinally of the work table 3 so that it may be properly aligned in the vertical plane of the periphery of the grinding wheel 6. The base 24 of the clamp is mounted for transverse adjustment on the bed 15. Its forward portion extends downwardly and overhangs the forward edge of the bed 15 in which is provided a T-slot 27 and bolts 28 having their heads 29 in said T-slot permitting movement of the clamp 24 transversely of the bed 15 and provide means for fixing the clamp in the desired position. An adjusting screw 30 is threaded into the base 24 of the clamp and has a head 31 in which is provided a groove to receive a guide 32 which is fixed to the bed 15 by a bolt 33 having its head in the T-slot 27. Each side of the base 24 of the clamp is provided with a screw threaded opening to receive the adjusting screw 30 so that the adjusting screw and its guide 32 may be located on

either the right or left hand side of the clamp as desired.

Operation

The machine is set up with the work holding jig 8 and the bed 15 of the grinding wheel dresser rigidly attached to the reciprocating table 3 but inasmuch as the clamping bolts 8 and 16 for the jig and bed respectively both act in the T-slot 10 in the table 3 the lateral positions of the jig and bed are arbitrarily established and cannot be adjusted relative to each other. The work 12 is clamped in the jig 8 and by conventional adjusting means (not shown) commonly provided in a grinding machine the grinding wheel is adjusted both vertically and laterally relative to the work and, assuming that the periphery of the grinding wheel has been originally dressed to the proper shape the grinding operation is accomplished by reciprocating the bed 3 which carries the work 12 backward and forward beneath and in contact with the grinding wheel.

Eventually the grinding operation will destroy the perfect contour of the grinding wheel and require its surface to be redressed and for this operation reciprocation of the table 3 is stopped and the grinding wheel dresser, which during the grinding operation had been removed from the bed 15, is placed upon said bed and the templet 22 is properly located relative both to the periphery of the grinding wheel and the position of the work 12 in the jig 8. To locate the templet 22 directly under or in the same vertical plane as the periphery of the grinding wheel 6 the templet may be adjusted by moving its shank 23 longi-

tudinally in the clamp 24 or the longitudinal position of the work table 3 may be adjusted to accomplish the desired alinement of the templet. The lateral or transverse adjustment of the templet is obtained, with its clamping bolts 28 loosened, by rotating the adjusting screw 30 and thereby moving the clamp 24 transversely on the bed 15 until it is accurately-positioned whereupon it is fixed in place by tightening the screws 28. This transverse positioning of the templet 22 must be made relative to the work 12 which is located in the jig 8.

We claim:

A grinding wheel dresser comprising a horizontal bed adapted to be rigidly attached to the work table of a grinding machine, a dressing tool freely slideable on the upper surface of said bed, a feeler on said dressing tool, a member having a part lying over and against the upper surface of said bed at an edge portion thereof and a part extending downwardly alongside said edge, means for releasably securing said member to said bed, a horizontal screw threading into said member and having a connection with the bed whereby turning said screw will adjust said member to different positions relative to the bed, a template and clamping means for securing said templet to and over said member, said templet having a projecting portion at the side thereof opposite its templet edge engaged by said clamp whereby upon release of the clamp, the templet may be adjusted in a direction at right angles to the adjustment of the member upon which it is mounted.

HENRY W. KROPP.

ARTHUR J. BRICKNER.
